UNITED STATES PATENT OFFICE

NED A. WAGERS, OF APPOMATTOX, VIRGINIA.

SCHOOL DESK AND SEAT

Application filed March 7, 1930. Serial No. 434,042.

This invention relates to an improvement in school desks and seats and has as its general object to provide a combined desk and seat, for school use, which will present advantages over the ordinary desks and seats of this type.

It is a well known fact that school furniture is subjected to rather rough usage and therefore the present invention contemplates 10 the provision of a combined desk and seat construction which will be exceptionally substantial and in which the seat member may be firmly supported in both lowered and raised positions.

Another object of the invention is to provide in an article of furniture of this class, a novel means for supporting the seat, which means will be so constructed as to firmly support the seat in lowered position for use 20 with minimum strain on the pivotal connection between the seat construction and the desk structure.

Another object of the invention is to provide, in a combined desk and seat, novel 25 means for limiting the movement of the seat to upright position, and which means will preclude any likelihood of the seat forcibly striking the desk top or the back of the seat when the seat is adjusted to such 30 position.

This invention also consists in certain other features of construction, and in the combination and arrangement of the several, parts, to be hereinafter fully described, 35 illustrated in the accompanying drawings and specifically pointed out in the appended claim.

In describing my invention in detail, reference will be had to the accompanying drawings wherein like characters denote like or corresponding parts throughout the several views, and in which:

Figure 1 is a view in side elevation of a 40 combined desk and seat constructed in accordance with the invention, the seat being shown in lowered position, for use.

Figure 2 is a front elevation of the structure with the seat in the position shown in 45 Figure 1.

Figure 3 is a view similar to Figure 1 showing the seat in elevated position.

Figure 4 is a top plan view of the structure, the seat being shown in lowered position.

Figure 5 is a perspective view of the structure, the seat being shown in elevated position.

The desk structure comprises a body 1, the top of which is indicated by the numeral 2, and the said body is supported by front legs 3, and rear legs 4, these legs being bolted or otherwise secured at their upper ends to the outer sides of the ends of the body 1. Each of the legs 3 has its forward edge, throughout its upper portion curved gradually, as indicated by the numeral 5, so as to conform to the curvature of the back of the seat, which is indicated by the numeral 6. For a purpose to be presently described, the forward edge of each leg at the lower end of the curved portion 5 is extended downwardly and then curved upwardly and thence forwardly so as to provide a seating notch, indicated by the numeral 7. Braces 8 are secured to and connect and relatively brace the legs 3 and 4 below their secured upper portions, and other braces 9 extend between and are secured to and connect and brace the legs 3 and 4 above their upper ends, and the forward ends of the braces 8 are cut on a curved line so as to conform to the contour of the rear side of the backrest 6 at the lower portion thereof. A foot rest 10 is mounted at 45 its ends upon the braces 9 and secured thereto in any suitable manner. The seat unit comprises a pair of arms which are indicated by the numeral 11 and these arms are pivotally mounted between their ends upon the front legs 3 by means of a rod 12 which is fitted at its ends through openings in the legs 3 and the arms 11, washers 13 and nuts 14 being fitted onto the ends of the rod 12, whereby to snugly connect the arms 50 with the legs.

It will be observed by reference to Figure 1 that the notch 7 is spaced inwardly from the lower portion of the forward edge of each leg so that ear portions 15 are pro-

vided in front of each seating recess or notch 7.

Figures 1 and 2 of the drawings illustrate the seat in lowered position or in other words in position for use and it will be observed, and particularly by reference to Figure 1 that when the seat is in this position, the rear portions of the arms 11 will engage at their upper edges against the under sides of the respective braces 8, so that a very firm support is provided for the seat. Figures 3 and 5 illustrate the seat in raised or elevated position as when not required for use, and, in this position of the seat, the rear edge of the seat bottom will rest in the notches or recesses 7 and therefore the upward and rearward swinging movement of the seat in the position shown in these Figures will be limited so that the forward portion of the seat will not scrape forcibly against the backrest 6 if the seat is quickly or forcibly swung upwardly. The seat bottom, backrest and desk top may all be made of one piece of wood, suitably shaped, or from tongued and grooved material.

What I claim is:—

A school desk and seat comprising front and rear legs and the front legs disposed on an inclined plane and the rear legs disposed vertically to position the upper ends of the front and rear legs in close proximity to each other with the lower ends of the legs spaced a considerable distance to provide a firm supporting structure, a desk body connected to the upper ends of the legs, a seat back secured to the front legs and the latter having notches below the lower edge of the back to provide shoulders, arms pivoted intermediate their ends to said shoulders, a seat secured to the arms forwardly of the pivots, upper and lower braces connecting the front and rear legs and the upper braces engaged by the arms when in one position to support the seat in an operative position, and a strip forming a foot rest connecting the lower braces and co-operating therewith in firmly bracing the legs.

In testimony whereof I affix my signature.

NED A. WAGERS.
